United States Patent

Des. 239,894
Patented May 18, 1976

239,894

FOOD DISPENSING BAR OR SIMILAR ARTICLE

Thomas C. Inman, 3607 Bainbridge Blvd.,
Chesapeake, Va. 23324

Filed June 5, 1974, Ser. No. 476,342

Term of patent 14 years

Int. Cl. D6—04

U.S. Cl. D6—144

FIG. 1.

FIG. 2.FIG. 3.FIG. 1 is a perspective view of a food dispensing bar or similar article showing my design;

FIG. 2 is a view in front elevation; and

FIG. 3 is a view in side elevation thereof.

The other side not shown is a mirror image of the side that is shown and the rear is plain and not ornamented.

I claim:

The ornamental design for a food dispensing bar or similar article, as shown and described.
